UNITED STATES PATENT OFFICE.

HARRY MORRIS, OF CHICAGO, ILLINOIS, ASSIGNOR TO MORRIS, MANN & REILLY, OF CHICAGO, ILLINOIS, A CORPORATION OF ILLINOIS.

NECKLACE.

Application filed August 2, 1924. Serial No. 729,743.

To all whom it may concern:

Be it known that I, HARRY MORRIS, a citizen of the United States, residing at Chicago, in the county of Cook and State 5 of Illinois, have invented new and useful Improvements in Necklaces, of which the following is a specification.

This invention relates to improvements in necklaces, and more especially to a complete necklace having a major flexible portion consisting of a string of pearls, beads, or the like, the ends of said string being fastened together by an ornamental part or parts, as will be described more in detail 10 hereinafter. There also may be provided a clasp by which the necklace may be opened.

My improved necklace is so designed that it is attractive and ornamental in appearance and will also retain a desired position 20 around the neck of the wearer. In necklaces, the pearls are frequently graded in size, so that it is desirable to keep the largest pearl thereon in the center at the front of the wearer. It is also often desirable to 25 keep the clasp of the necklace at the back. Necklaces are also often provided with ornamental members adjacent the clasp which are intended to remain in the center at the back of the wearer. It will be seen that 30 in all of such types of necklaces, it is desirable to prevent the necklace from shifting about on the neck of the wearer. In my improved necklace this shifting of position of the necklace is prevented.

Other features and advantages of my invention will appear more fully as I proceed with my specification.

In that form of device embodying the features of my invention shown in the accompanying drawings, Figure 1 is a view of the complete necklace, Fig. 2 is a view on an enlarged scale of a portion of the necklace to be described more in detail hereinafter, and Fig. 3 is a view taken as indicated by the line 3, 3 of Fig. 1.

As shown in the drawings, the major length or portion of the complete necklace comprises a flexible string of pearls, beads, or the like, as indicated by 10, 10. 11 is a conventional indication of a clasp at one end of the string passing through the eye 12. The clasp 11 may be of any desired form so that the same may be engaged through the eye 12 or released therefrom, in order 50 to open the necklace at this point. Between

the clasp 11 and the other end of the string as indicated by 10^a, there are provided three stiff links, the center link being indicated by 13, and the end links by 14, 14. Each of the links 14 is hinged to the link 13 at 60 14^a. Each link is also curved to conform to the curvature of the neck of the wearer.

The outer faces of the three links 13, and 14, 14, may be ornamented in any desired manner. These three links, for example, 65 may be ornamented or designed in order to resemble a bar pin. Such representations of bar pins have been very much in vogue in necklaces of this kind. The ordinary representation of a bar pin, however, is objectionable owing to its length and rigidity. This objection, in the present invention, however, is overcome by the hinges 14^a, 14^a. These hinges aid also in permitting the links 70 13 and 14, 14, to conform to the curvature 75 of the neck of the wearer.

The inner surfaces of the links 13 and 14, 14 are concaved as indicated by 15 (see Fig. 3). Such concavity in the inner surface of the links assists in retaining the 80 necklace in the proper position on the wearer. The flesh of the wearer projects into such cavities thus preventing the slipping of the links. If the links are made 85 flat, they will not press into the flesh of the wearer to such an extent and will consequently slip around more easily.

The three links 13 and 14, 14 together with the clasp member 11 virtually form 90 the entire clasp. That is, the three hinged links are to be considered as a part of the clasp, as this word is used in its general sense. In other words, the entire clasp therefore comprises not only the separable 95 elements used to open the necklace but also the three links 13, 14 and 14 which make the clasp ornamental. For example, as has been stated before, the clasp may resemble a bar pin. It is to be noted that the three links 13, 14 and 14 are fashioned so that 100 they form a unitary structure, such unitary structure here resembling a bar pin forming a part of the entire clasp. Heretofore when clasps have thus been made in the form of a bar pin, or any resemblance to the bar pin it has been found that the part of the clasp resembling the bar pin, because of its length, would not easily and naturally conform to necks of different curvature.

110 This objection has been overcome in the

present device by making the long member of the clasp which here resembles a bar pin of three sections hinged together.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

What I claim as new, and desire to secure by Letters Patent, is:

1. A necklace clasp consisting of a plurality of elongated links hinged together.
2. A necklace clasp consisting of a plu-

rality of elongated curved links hinged together.

20

3. A necklace clasp consisting of a plurality of elongated links hinged together the inner surfaces of said links being concaved.

25

4. A necklace clasp consisting of a plurality of elongated curved links hinged together the inner surfaces of said links being concaved.

25

5. A necklace comprising a major flexible portion consisting of a string of beads; a minor curved stiff clasp portion having its inner side concaved; and means for detachably securing one end of the flexible portion to one end of the curved stiff portion.

30

Witness my hand this 31 day of July,
A. D. 1924.

HARRY MORRIS.
